UNITED STATES PATENT OFFICE.

EDWARD A. EUSTICE, OF GALESBURG, ILLINOIS.

WASHING MACHINE.

Application filed January 10, 1921. Serial No. 436,393.

To all whom it may concern:

Be it known that I, EDWARD A. EUSTICE, a citizen of the United States, and a resident of the city of Galesburg, county of Knox, 5 and State of Illinois, have invented certain new and useful Improvements in Washing Machines, of which the following is a specification.

My invention relates to washing machines 10 and it has for its principal object the provision of a new and improved form and arrangement of parts by which an improved operation may be had for washing clothes, serving to make the operation of washing 15 easier and quicker, and giving better results.

Other objects will appear hereinafter.

The invention will be best understood by reference to the accompanying drawings forming a part of this specification, and in 20 which,

Fig. 1 is an end view of a washer embodying my improved construction.

Fig. 2 is a vertical cross section through my machine,

Fig. 3 is an end view of the revoluble element of my improved machine,

Fig. 4 is an enlarged cross sectional view taken substantially on line 4—4 of Fig. 3,

Fig. 5 is a fragmentary view, being a 30 cross section taken on line 5—5 of Fig. 3 and

Fig. 6 is a view showing a modification of the means for mounting the holder.

Referring to the drawings, 10 indicates a tub of any approved type supported upon a 35 framework 11 and closed at its upper end by a lid 12 of any approved type. Revolvably mounted in the ends of the tub 10 is a shaft 13 which has one end portion extending beyond the end of the tub and carrying 40 a pinion 14 by which the shaft is adapted to be given either a continuous rotation or an alternating rotary motion as may be desired.

The revoluble element of my improved 45 washer comprises two holders which are mounted in spaced relation with respect to each other upon opposite sides of the shaft 13, the two holders being removably mounted in position and being braced with 50 respect to each other for insuring the desired rigidity in operation.

Each of the holders, in the construction shown, comprises two heads 15 which are semi-circular in shape, being spaced at a 55 distance apart and being joined together by sheet metal 16 provided with perforations

throughout its entire area, the heads 15 and the sheet metal 16 serving to provide a reticulated structure of substantially semi-cylindrical shape. As is shown in Fig. 2, 60 a section 17 of the sheet metal of each of the holders is hingedly mounted upon the heads 15, the doors thus provided being adapted to be held closed by turn buttons 18.

My semi-cylindrical holders are secured 65 in position upon the shaft 13 within the tub 10 by the use of brackets 19 fixedly mounted upon the shaft 13 at the opposite ends of the tub. Each of the heads 15 is provided with a bearing member 20 on its outer face 70 adapted by engagement with the adjacent bracket 19 to position the holder with respect to the shaft. Slide blocks 21 which are movably mounted upon the heads 15 are adapted to be brought into engagement with 75 the ends of lugs 22 formed on the brackets 19 for securing the heads firmly in position upon the brackets, thumb screws 23 being provided for holding the slide blocks 21 releasably in position. As will be readily 80 understood, when one of the holders is placed in centered position between the brackets 19, the slide blocks 21 are adapted to be moved readily and quickly into engaging position and tightened by means of 85 the thumb screws 23 for securing the holders firmly in position. The holders are further detachably connected together by means of hinged members 24 carried by one of the 90 holders and releasably connected to the other holder by means of flat headed screws 25 which pass through slots 26 in said hinged members, as is clearly shown in Figs. 3 and 5.

When it is desired to use the machine, the 95 cylindrical holder comprising the two sections as above described is turned into position with one of the doors 17 uppermost so as to facilitate placing the desired quantity of clothes to be washed into the section. The shaft 13 is then given a half rotation 100 to bring the other door 17 uppermost for filling the other section 15 of the holder. With the holders 15 filled with the proper quantity of clothes, and with the tub 10 filled with hot water to the desired point, 105 the shaft 13 is given a rotary movement for carrying the holders 15 alternately into and out of the water. As will be readily understood, when one of the holders is in uppermost position, the water is caused to escape 110 from the holder and from the clothes. Im-

mediately following this, the clothes are again immersed in the water by the continued rotation of the shaft. By reason of this alternate immersion of the clothes in the water and the movement out of the water, a maximum of cleaning effect is attained, rendering my machine very effective for cleaning purposes. The cleaning is also enhanced by the sliding movement 10 of the clothes along the perforated walls of the holder, and by the squeezing effect when the clothes slide into the converging side portions of the holder sections.

In Fig. 6, I have shown a construction in which the use of a shaft running through the holder is avoided. This result is effected by the provision of brackets 27 and 28 equipped with studs or stub shafts 29 and 30, respectively, which are revolvably supported in bearings in the ends of the tub 10. The shaft 30 has the driving gear 14 mounted thereon for giving rotary movement to the holder sections 15 in the manner above described, the holders being rigidly secured in position between the brackets by the use of any suitable means. If desired, one or both of the holders may be made readily removable from the brackets.

I have found in practice that my machine is very effective, both when the shaft 13 is given continuous rotation in one direction, and when it is given a plurality of rotations in one direction and then a plurality of rotations in the opposite direction. I have found that in the use of my machine, there is no tendency of the clothes to become twisted into a ball by continued rotation of the holders in one direction. By the provision of a device of this type, which is adapted for attaining highly efficient results without the use of reversing gear mechanism such as is required for producing the alternating rotation employed with some types of washing machines, I am enabled 45 to build my machine at a reduced cost, and with greater ease than would otherwise be possible.

By the use of my construction as above described, the operation of removing the clothes from the machine is greatly facilitated. With one of the sections 15 in its uppermost position, the door 17 will be opened, giving direct access to the clothes from which the major portion of the hot water will have been drained by reason of the elevated position of the holder. Thereafter the other section 15 is brought to its elevated position for removal of the clothes therefrom. By reason of making one or 60 both of the sections 15 easily removable from its mounting means, easy access can be had to the tub for cleaning it without the necessity for lifting out in one piece the entire rotating element.

65 While I prefer to form my improved

holder members of perforated sheet metal as shown, it will be understood that I do not restrict myself to that particular form of structure except as hereinafter specifically claimed since other forms of reticulated holders may obviously be used for the practice of my invention broadly, the essential feature being that the water is permitted to pass into and out of the holder easily and quickly.

75 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

80 Having described my invention, what I claim as new and desire to secure by Letters Patent is:

85 1. A washing machine comprising a tub adapted to contain water, a substantially cylindrical holder formed in separate clothes containing sections spaced apart and having perforated walls, a rotatable shaft extending through the tub between the sections, carriers rigid upon said shaft, and means for 90 releasably attaching the sections to the carriers, whereby said sections may be released from the carriers and bodily removed from the tub, rotation of the shaft causing the holder sections to swing into and out of 95 water in the tub.

100 2. A washing machine comprising a tub adapted to contain water, two substantially semi-cylindrical reticulated holder members, releasable means for rigidly holding the members in spaced relation, and means for 105 mounting said holder members revolvably in position in said tub, said means including carrying elements releasably connected with the ends of the members, and a shaft extending through the tub between the members and having the carrying elements rigidly mounted thereon, rotation of the shaft serving to revolve the members and move them alternately into and out of the water in the 110 tub.

115 3. A washing machine comprising a tub adapted to contain water, a shaft revolvably mounted in said tub, brackets fixedly mounted on said shaft within said tub, substantially semi-cylindrical reticulated holder members removably mounted between said brackets in spaced relation with respect to each other on opposite sides of said shaft, and releasable connections between said 120 holder members at opposite sides of said shaft.

125 4. A washing machine comprising a tub adapted to contain water, a shaft revolvably mounted in said tub, brackets fixedly mount- 130

ed on said shaft within said tub, an arcuate reticulated holder, bearing members on opposite ends of said holder adapted by engagement with said brackets to position the 5 holder with respect to said shafts, and detachable means for securing said holder upon said brackets.

5. A washing machine comprising a tub adapted to contain water, a plurality of reticulated holder members adapted to contain clothes to be washed, means carried by one of said members and releasably engaging the other member for holding said members rigidly in spaced relation adapted to permit 15 ready detachment of one of the members, and means for moving said members in turn into and out of the water in said tub.

6. A washing machine comprising a tub adapted to contain water, a rotatable shaft 20 extending through the tub, bracket elements carried by said shaft within the tub and having arms extending radially of the shaft, reticulated clothes holding compartments positioned in the tub and extending longi-

tudinally therein with the shaft between 25 the compartments, and means carried by the ends of the compartments for releasably engaging the arms of the brackets carried by the shaft.

7. A washing machine comprising a tub 30 adapted to contain water, bracket elements rotatably mounted in the tub and having arm extensions, clothes containers positioned in said tub and formed of perforated material, means carried by the clothes containers for releasably engaging the arms of the bracket elements, and fasteners carried by the clothes containers at opposite sides of each bracket for releasably connecting the clothes containers. 40

In testimony whereof I have signed my name to this specification in the presence of two subscribing witnesses.

EDWARD A. EUSTICE.
